(57) **CLAIM**

The ornamental design for a caster assembly, as shown and described.

DESCRIPTION

FIG. 1 is a perspective view of a caster assembly showing the new design, in exemplary use;

FIG. 2 is a perspective view of the caster assembly of FIG. 1;
FIG. 3 is another perspective view of the caster assembly of FIG. 1;

FIG. 4 is a side view of the caster assembly of FIG. 1;
FIG. 5 is an opposite side view of the caster assembly of FIG. 1;

FIG. 6 is an end view of the caster assembly of FIG. 1;
FIG. 7 is an opposite end view of the caster assembly of FIG. 1;

FIG. 8 is a bottom view of the caster assembly of FIG. 1;
FIG. 9 is a top view of the caster assembly of FIG. 1;
FIG. 10 is a perspective view of the caster assembly of FIG. 1, showing the wheel rotated, in exemplary use.

FIG. 11 is a perspective view of the caster assembly of FIG. 1, showing the wheel rotated as in FIG. 10;

FIG. 12 is another perspective view of the caster assembly of FIG. 1, showing the wheel rotated as in FIG. 10;

FIG. 13 is a side view of the caster assembly of FIG. 1, showing the wheel rotated as in FIG. 10;

FIG. 14 is an opposite side view of the caster assembly of FIG. 1, showing the wheel rotated as in FIG. 10;

FIG. 15 is an end view of the caster assembly of FIG. 1, showing the wheel rotated as in FIG. 10;

FIG. 16 is an opposite end view of the caster assembly of FIG. 1, showing the wheel rotated as in FIG. 10;

FIG. 17 is a bottom view of the caster assembly of FIG. 1, showing the wheel rotated as in FIG. 10; and,

FIG. 18 is a top view of the caster assembly of FIG. 1, showing the wheel rotated as in FIG. 10.

The broken lines in the drawings depict environmental subject matter only and form no part of the claimed design.
